T. HAND.

BALL COCK FOR WATER CLOSET CISTERNS.

No. 595,063.

Patented Dec. 7, 1897.

UNITED STATES PATENT OFFICE.

THOMAS HAND, OF PAWTUCKET, RHODE ISLAND.

BALL-COCK FOR WATER-CLOSET CISTERNS.

SPECIFICATION forming part of Letters Patent No. 595,063, dated December 7, 1897.

Application filed April 14, 1897. Serial No. 632,104. (No model.)

To all whom it may concern:

Be it known that I, THOMAS HAND, a citizen of the United States, residing at Pawtucket, in the county of Providence and State of Rhode Island, have invented certain new and useful Improvements in Ball-Cocks for Water-Closet Cisterns; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to ball-cocks for water-closet cisterns; and it consists, essentially, of an auxiliary float connected to the ball-cock and adapted to be made operative automatically by the water in the cistern or 20 tank whenever the water therein rises above a predetermined or fixed level, all as herein-after set forth and claimed.

The object I have in view is to provide ball-cocks of the class referred to with a simple, 25 efficient, and comparatively inexpensive attachment for indicating that water is running to waste from the cistern. It is well known that the ball-cocks for cisterns are liable to leak from various causes, one reason being 30 that the packing must not press too snugly against the valve member, as otherwise the friction would be too great to allow the cock or valve to move readily with the changes in 35 the water-level when the closet is being "flushed." I may add, too, that the pressure of the inlet-water is comparatively great. Therefore the water is liable to escape past the packing. The water thus escaping may be a small stream, but it is continuous (until 40 the valve is repacked) and overflows into the water-closet hopper and sewer connection.

My invention in no wise interferes with the free working of the ball-cock when the latter is in the normal condition—that is, it readily 45 opens and closes by the action of the ball-float and the changing water-level, as usual; but in case the valve or cock leaks to an appreciable extent, so that the water rises in the cistern to a predetermined point, it fills 50 the auxiliary float. The latter then falls or sinks to the bottom of the cistern, thus increasing the weight upon the arm of the ball-

cock and keeping the latter snugly closed even after the flushing charge has been discharged from the cistern. Now whenever 55 the succeeding user attempts to wash out the hopper no water will follow the "pull." The failure will be reported, and an investigation will disclose the fact that the valve needs repacking or some other attention. Upon correcting the defect and simply emptying the water from the auxiliary float the several parts will again become normally operative.

In the accompanying drawings, Figure 1 is a longitudinal section taken through a well-known form of cistern and having my improvement combined with the ball-cock, the parts being in the normal position, all the valves being closed. Fig. 2 is a corresponding transverse section taken on line $x-x$ of 70 Fig. 1. Fig. 3 is the same as Fig. 2, but showing the auxiliary float dropped to its limit; and Fig. 4 is a perspective view of one form of said float.

I may state here that my invention may be 75 arranged and adapted to be attached to various kinds of ball-cocks in which the actions are controlled by the changing level of the water contained in the cisterns or tanks in which they are mounted.

In the drawings, A indicates the apparatus complete, the same being employed for wash-out water-closet hoppers or bowls. As drawn, the cistern a, the ball-cock c, its arm d, and float-ball d' are constructed and adapted for 85 operation substantially as common. The overflow-pipe or upright s' is provided with an outlet-valve at the bottom, a pull p, a pull-lever s, and connection g, uniting the lever and valve, also as common.

My invention resides, essentially, in combining the auxiliary float f with the ball-cock. The float itself is hollow and watertight and has an inlet-opening f' therein at or near the top, through which the water may 95 enter.

f² is an air or vent outlet in the top of the float, and f³ are guide-ears.

h indicates a suitable standard mounted in a bracket b, secured to the cistern a. The lower portion of the standard forms a guide for the float f, as clearly shown in Fig. 2. The upper part of the standard is bent to form a horizontal arm h', on which latter are

located the two depending adjustably-secured pulleys r r . A flexible connection m extends from the float f up to and around the said pulleys and thence down to the arm d of the ball-cock. At a point in the connection m above the arm d I prefer to locate a weight w , this latter exceeding the weight of the empty float f and the connection m . The relative height or position of the empty float f is controlled or regulated by the stop or collar n , adjustably secured to the standard h , as clearly shown.

By means of the arrangement just described it will be seen that when the valve or cock c is working normally the empty float f will be held in position against the stop n through the medium of the counterweight w , the slackness of the connection m being between the said weight and arm d , thereby permitting the latter to swing freely on its fulcrum. (See Figs. 1 and 2.) In case the valve leaks sufficiently to elevate the water-level, say, to the line k , Fig. 2, the water will then gradually flow into the float f , via opening f' , until the volume of water therein preponderates over the weight w and causes the float to sink to the bottom of the cistern, thereby at the same time elevating the weight, the connection m then being taut throughout its length and thus automatically preventing the ball d' from falling to open the cock c when the next flushing or wash-out takes place.

By means of the adjustable holders t and pulleys r the latter can be readily set to any desired position with respect to the ball-cock arm, &c., and by loosening the set-screw b' the standard-arm h' may be swung around to any position within its limits. The level of the water-line k may be varied as desired by simply changing the length of the connection m and altering the position of the stop n correspondingly.

From the foregoing it is clear that the device operates automatically to keep the ball-cock or valve fully closed until it is again reset or readjusted by hand.

In order to further insure the closing of the ball-cock and to prevent the float f from accidentally rising after it has dropped away from the upper stop n , the device may be

provided with a light spring u , having its lower or free end adapted to spring outwardly over the float, thereby, as it were, automatically locking the latter in position, substantially as represented in Fig. 3.

55

Without materially departing from the spirit of my invention the device may be adapted to various arrangements of ball-cocks wherein the latter are employed to admit a predetermined volume of water into a reservoir at intervals.

I claim as my invention and desire to secure by United States Letters Patent—

1. In a flushing or wash-out apparatus of the class herein described, the combination 65 with a suitably-mounted ball-cock adapted to be made operative substantially as usual by changes in the height of water contained in the cistern or tank, of an auxiliary hollow float connected to said ball-cock, and communicating with the water of said tank, and means for limiting the movements of the float, constructed and arranged whereby in case the water rises to a predetermined point above the normal level it then flows into said auxiliary float, thus sinking or depressing the latter and preventing the ball-cock from again opening until the float is readjusted, 75 substantially as set forth.

2. The combination with a ball-cock, of a 80 vertically-guided auxiliary float provided with an inlet-opening for water, and a suitable connection uniting said float and the arm of the ball-cock, substantially as described.

3. In an apparatus of the class described, 85 provided with a suitable cistern or tank, as a , the combination with the usual ball-cock mounted in said cistern, of a vertically-guided auxiliary hollow float f , a suitably-mounted counterweighted flexible connection uniting 90 said float and the arm of the ball-cock, and means for adjusting the position of the float, substantially as described and for the purpose set forth.

In testimony whereof I have affixed my signature in presence of two witnesses. 95

THOMAS HAND.
